UNITED STATES PATENT OFFICE.

GEORGE A. SEIB, OF ILION, NEW YORK, ASSIGNOR TO REMINGTON TYPEWRITER COMPANY, OF ILION, NEW YORK, A CORPORATION OF NEW YORK.

TYPE-WRITING MACHINE.

1,203,795.

Specification of Letters Patent. Patented Nov. 7, 1916.

Application filed August 20, 1915. Serial No. 46,444.

To all whom it may concern:

Be it known that I, GEORGE A. SEIB, a citizen of the United States, and resident of Ilion, in the county of Herkimer and State of New York, have invented certain new and useful Improvements in Type-Writing Machines, of which the following is a specification.

My present invention relates primarily to ribbon mechanism for typewriting machines and its general object is to provide new and improved mechanism of the character specified.

The invention in its present embodiment provides a support for the line gage and for the lever or device which actuates the ribbon vibrator said support being mounted independently of but shiftable with the case shifting mechanism of the machine through a yielding connection between the two and being arrested at the end of the shift by a stop on the shifted element with which stop the support is constantly engaged.

The purpose of the construction is to insure a practically unvarying extent of shifting movement for the ribbon vibrator and for the line gage notwithstanding possible variation, due to yielding or give in the case shifting parts.

More specifically the construction is designed as an improvement on that disclosed in the application of John H. Barr, Serial No. 3,474, filed January 21, 1915, which has eventuated in Patent No. 1,153,668, granted September 14, 1915.

To the above and other ends my invention consists in the features of construction, combinations of devices and arrangements of parts hereinafter described and particularly pointed out in the claims.

In the accompanying drawings illustrating the preferred form of my present invention, Figure 1 is a side elevation, partly in section, of a Remington typewriting machine embodying my invention, parts of the machine being omitted. Fig. 2 is a vertical transverse sectional view taken on a plane indicated by the dotted line $x-x$ in Fig. 1 and looking forward. Fig. 3 is a fragmentary perspective view of parts of the case shifting mechanism. Fig. 4 is a side elevation, partly in section, showing the ribbon vibrating and controlling mechanism in lower case position. Fig. 5 is a perspective view of parts of the ribbon vibrating and con-

trolling mechanism. Fig. 6 is a view corresponding to Fig. 4 but showing the part in shifted or upper case position. Fig. 7 is a face view of the ribbon vibrator and its guide. Fig. 8 is a perspective view of the vibrator actuators and the associate rocking frame.

Referring to Figs. 1, 2 and 3 the main frame of the machine is shown as comprising a base 1, posts 2 and a top plate 3 that supports fixed guide rails 4 on which runs a carriage truck 5. A platen 6 is mounted in a platen frame shiftably connected with the truck, the relatively movable truck and frame together constituting a platen carriage. The platen frame comprises end bars 7 and a connecting cross bar 8 that extends lengthwise beneath the platen. The platen axle 6^a bears in the end bars 7 and these end bars are pivotally connected by devices 9 with the truck 5. A roller 10 journaled on the cross bar is adapted to run on a shift rail 11 that is supported by upright arms 12 secured at their upper ends to the rail 11 which, with the arms, constitutes a rigid frame or bail. The lower end portions of the arms 12 are bent or turned forward to provide ears 13 which are pivotally connected at 14 to levers 15, said levers bearing pivotally on a cross rod 16 that is supported by the sides of the base. Collars 17 fixed to said rod outside the levers 15 by set screws 18 prevent the levers from endwise displacement on said rod. Secured to the forward arms of the levers as by rivets 19 are the parallel vertical end portions of a U-shaped bail plate 20, the levers and bail thus providing a rigid frame which bears loosely on the rod 16 and is maintained in place by the collars 17. Pivoted at 21 on the sides of the bail 20 are forwardly extending arms 22, each provided with a shift key 23. Underlying and co-operative with the rear portions of the arms 22 are the free upwardly and outwardly curving ends of a leaf spring 24 that is secured to the horizontal portion of the bail 20. The construction provides a yielding connection between the shift keys 23 and the levers 15 that support the shift rail. The upward movement of the shift rail is limited by the usual stops 25 on the ends of the carriage truck, said stops acting through the carriage axle 6^a to arrest the shifted parts. In addition stops are provided for positively arresting the arms 22, 110

said stops being in the form of adjustable screws 26 that are secured in a stationary cross bar 27, said screws projecting upward into the path of the arms 22. Counterbalancing springs 28 are connected at their front ends to lateral pins 29 projecting outward from the upright ends of the bail 20, the rear ends of said springs having fixed anchorages 30. The left-hand shifting arm 16 or lever 22 is provided with the usual locking devices for retaining the platen in its uppermost or shifted position. Said devices comprise a spring pressed arm 31 pivoted on the left-hand arm 22 and provided with a key cap or button 32, the lower end of said arm terminating in a hook 33 which is adapted to engage with a fixed abutment 34 to rock the shift frame down when the key 32 is actuated. Printing key levers 35 are provided with keys 36 and are connected by links 37 with sub-levers 38, said sub-levers in turn being connected by links 39 with front-strike type bars 40 mounted on hangers 41 secured to a stationary segment or support 42. A universal bar 43 underlies the key levers and is carried by arms 44 depending from crank arms 45 which project rearward from the transverse rock shaft 46 having stationary end pivots. Projecting rearward from said rock shaft near its middle is an arm 47 which is connected by a link 48 with certain of the escapement devices not herein shown but which are of ordinary Remington construction.

35 Ribbon spools 49 are supported one at each side of the machine below the top plate on horizontal shafts 50 and a ribbon 51 is wound on said spools and led upward therefrom through openings in the top plate, thence inward over stationary guides 52 and through guide openings in the head or upper portions of a ribbon carrier or vibrator comprising a pair of parallel wire guide loops 53 rising from a slotted body portion 54, said vibrator being arranged about centrally between said stationary guides 52. For turning the spools in alternation to feed the ribbon longitudinally back and forth, means are provided which 40 operate on the shafts 50. Said means comprise (as in the Remington No. 10) beveled pinions 55 mounted on the rear ends of said shafts and adapted to mesh with beveled driving pinions 56 spaced apart on a ribbon driving shaft 57 which is connected through constantly engaged beveled pinions 58 and 59 with a spring drum 60, said drum being connected by a strap 61 with an arm 62 on the carriage truck 5. When the carriage is drawn leftward under the pull of the spring drum the driving shaft 57 will be turned, causing one or the other of the ribbon spools to turn and wind the ribbon thereon, thus feeding the ribbon longitudinally. Means preferably of the usual Rem-

ington construction are provided for moving the driving shaft 57 back and forth endwise to cause the driving pinions 56 to engage alternately with the pinions 55, thus reversing the direction of the ribbon feed. 70 The lower end of the ribbon vibrator 53, 54 is pivotally connected at 63 to the horizontally disposed arm 64 of a bell crank lever 65 which, as appears clearly from Figs. 1, 2, 4 and 5, further comprises an angularly disposed arm 66 and a brace 67. The arm 64 divides into two branches which terminate in ears 64^a that bear on a pivot rod 68. The mounting of said rod is novel and will be hereinafter described in detail. The 80 operating lever 65 is actuated by devices which are mounted on a bracket 69 fixed to the rear of the type bar support 42. Secured on the bracket is a fulcrum rod 70 on which are pivoted two actuators 71 and 72 85 that are respectively connected by links 73 and 74 with the arm 66 of the lever 65. The actuators are both constantly connected with the operating lever but means are provided for rendering them separately effective at 90 will to operate said levers, said means comprising a rocking frame 75 pivoted on the rod 70, the rocking frame having a slotted head 76 through which the actuators 71 and 72 pass, the downwardly extending arms of 95 said frame being connected by a cross rod 77. A spool 78 loose on the rod 77 is engaged by the slotted upper end of an angular plate 79 which is adjustably mounted on the arm 47 by means of two screws 80 and 100 81. The screw 80 passes through a round hole in said plate 79 while the screw 81 engages in a slot 82 in said plate. By loosening the screws the plate 79 may be adjusted by swinging it on the screw 80 as 105 a pivot, the swinging movement being limited by the ends of the slot 82. A vertically arranged set screw 83 threaded through the arm 47 and secured by a locking nut 84 cooperates at its lower end with a lateral lip 110 85 on the arm 79, said screw facilitating fine relative adjustments between the plate 79 and arm 47 and also positively transmitting the movement of the arm 47 to the plate 79 and thence to the rocking frame 75. The 115 construction is such that when the printing keys are operated the frame 75 is rocked or vibrated and a motion is transmitted therefrom to one or the other of the actuators 71 and 72 through the slotted head 76, the 120 actuators being selected by sliding the frame 75 endwise on the rod 70. As best appears from Fig. 8 the slot in the head 76 comprises an opening 76^a at the right and a smaller opening 76^b at the left, the two 125 openings being connected by a narrow passage-way or throat 76^c. By sliding the frame 75 toward the right until the actuator 72 is in the throat 76^c, said actuator will be rendered operative and its movement 130

when the frame 75 is rocked will be transmitted through the link 71 to the operating lever and ribbon vibrator. During this operation the actuator 71 will move idly in the opening 76^b. When it is desired to render the actuator 71 operative the frame 75 is slid toward the left until said actuator is in the throat 76^c and the actuator 72 is positioned for idle movement in the opening 10 or slot portion 76^a. For mimeographing purposes the frame 75 is also capable of adjustment leftward to bring both actuators in the opening 76^a, thereby rendering the frame inoperative on the actuators when the 15 type keys are actuated. The sliding adjustments of the rocking frame and its cooperation with the actuators are explained more fully in the Barr patent aforesaid. The endwise shift of the frame 75 is accomplished by devices (Figs. 1 and 2) comprising a link 86 which connects said frame with a crank arm 87 fixed to a rock shaft 88 having stationary bearings and provided with a finger piece 89 which may be turned to adjust the frame 75. A pointer 90 on the rock shaft 88 co-operates with stationary indicating marks 91 to facilitate these adjustments. Detent devices for maintaining the frame 75 set in adjusted positions comprise a spring 20 plate 92 fixed to the shaft 88 and having perforations 93 which co-operate with a stationary lug 94. The above described devices for variably actuating the operating lever 65 are substantially like those described and 25 claimed in the Barr patent aforesaid except that the adjustable plate 79 and its associate parts replace a plain arm or plate found in the Barr construction.

Referring to the novel means for mounting and shifting the ribbon operating lever 65 to which means my present invention more especially relates, it will be seen from Figs. 1, 2, 4 and 5 that the pivot rod 68 of the lever 65 is mounted on a bail-like frame 95, this frame constituting a support for the operating lever and the ribbon vibrator. Said frame 95 comprises a cross portion 96 connecting two parallel, rearwardly extending side portions 97 from which extend 50 downward parallel extensions 98 while on the cross portions extend inclined upward and forward two arms 99 connected by a cross portion 100 having a downwardly projecting central ear 101, said cross portion 55 terminating at its ends in forwardly projecting lugs 102. The ear 101 carries a guide screw 103 which co-operates with a slot in the body portion 54 of the vibrator, as best shown in Fig. 7. The frame 95 is mounted 60 on sets of parallel links which are pivotally connected with the downward extensions 98 and in turn are pivoted on the stationary support. The upper pair of links 104 are pivotally connected at 105 and at their rear 65 ends to pivot pins 106 on the side portions

of a bracket 107 shaped like an inverted U, which bracket is secured by screws 108 to the under side of the top plate. The lower links 109 are pivotally connected at their forward ends by laterally projecting pivot pins 110 with the lower ends of the extensions 98 while the rear end portions of said links are pivoted at 111 to the sides of the bracket 107. Back of the pivots 111 the links 109 are connected by an integral cross portion or bar 112, the links 109 and the cross bar 112 constituting a rigid bail which has the effect of synchronizing the movements of the links. Diagonal draw springs 113, one at each side, are hooked at their 80 ends into grooves on the pins 106 and 110. The tendency of the springs is constantly to lift or raise the supporting frame 95 and the operating lever 65 mounted thereon. A stud 114 extends rearward from the cross 85 bar 96 of the frame providing a bearing for a hardened roller 115. This roller is maintained by the springs 113 in constant contact with the horizontal lip or stop surface 116 of a stop bar 117 that extends longitudinally 90 of the frame bar 8 in rear thereof. The stop bar 117 is formed at its ends with vertical slots 118 which receive screws 119 by which the bar 117 is fixed at its ends to the platen frame. The screw and slot connection affords an up and down adjustment of the stop bar 117 and a variable setting of the stop or lip 116 in respect to the platen frame. By securing the stop bar only at its ends to the platen frame bar 8 any distortion or variation in the frame bar 8 due to stresses and strains to which it may be subjected has practically no effect on the stop bar and its lip 116, the bottom face of the lip at all times remaining substantially in 105 a single plane which is the same distance from the platen for both lower and upper case. The consequence is that the roller 115 which is always maintained in contact with this lip 116 maintains the pivot rod 68, the operating lever 65 and the ribbon vibrator in the same normal relationship with the platen in both case positions thereof, the vibrator automatically following the shifting movements of the platen. It will be 110 understood that in shifting from lower to upper case the support 95 moves upward bodily, carrying with it the operating lever and vibrator but that the actuators 71 and 72 will not be affected by the shifting movement. During said movement the links 73 and 74 swing upward about their respective points of connection with said actuators 71 and 72 as pivots. The shifted position of 115 the parts is shown in Fig. 6.

It will be observed that the link motion by which the up and down movement of the support 95 is controlled embodies at each end of said support what may be described as a double toggle, one toggle comprising 120

the link 104 and the extension 98 and the other toggle comprising the link 109 and the downwardly extending arm of the bracket 107. When in lower case position the toggles are the nearest to a straight line or dead center to which they ever come and at this time the associate spring 113 is extended to its greatest length and is most powerful. When the platen is shifted, the members comprising each toggle approach nearer each other and consequently require less of a pull from the spring so that though the spring weakens as its ends approach nearer together, it nevertheless exerts substantially the same effect on the toggles in upper case as in lower case position. As a consequence of this compensatory arrangement the pressure of the roller 115 on the lip 116 is maintained substantially uniform at all times. The points of connection of the spring 113 with the toggle or linkage devices may, of course, be varied as found desirable. On releasing the shift key the platen carrier and connected parts will be restored to lower case position as usual and the lip 116 pressing down against the roller 115 will overcome the springs 113 and force down to lower case position the support 95 together with the operating lever and ribbon vibrator.

The lugs 102 of the support 95 are confined loosely between parallel fingers 120 which are integral with and extend upward and forward from a plate 121 fixed to the rear of the segment or support 42. These fingers 120 coöperate with the lugs 102 to prevent sidewise displacement of the frame 95 during its up and down shifting movements, the fingers serving as guides for the frame.

In addition to supporting the pivot rod 68 the shiftable frame 95 provides a support for the line gage. This may be one of ordinary construction as illustrated in Figs. 2 and 4 where it is designated by the reference numeral 122. The gage is fixed to the front of the cross bar 96 by screws 123, a washer plate 124 being interposed between the heads of the screws and the lower portion of the line gage 122. By reason of its mounting on the shiftable support 95 the line gage is maintained in proper relationship with the printing face of the platen in both lower and upper case, the upper edge 122^a of the gage proper indicating or gaging accurately the bottom of the printing line in both case positions.

Besides their guiding function in connection with the frame 95 the fingers 120 serve additionally to prevent the paper fingers carried by the platen from ever getting in the path of the printing type bars. The paper fingers are of ordinary construction and slidably mounted on a supporting rod

125 which extends lengthwise of the platen 65 above the printing line and is supported at its ends from the end bars 7. There are two paper fingers 126 of ordinary construction, each slidably mounted on the rod 125 and extending upward in front of the 70 platen past the printing line thereon, each paper finger carrying at its top a roll 127 and having an outwardly off-set portion which is provided with a forwardly extending lip 128. The path of this lip is intercepted by the fingers 120 so that if the endwise movement of the carriage is continued far enough the lip 127 will contact with the associate finger 120 and arrest the paper finger 126, although the movement of the 80 carriage may continue after such arrest, the rod 125 sliding through the arrested paper finger. The relationship between the lip 128 and the main portion of the paper finger is such that, as will be understood from Fig. 85 2, the body of the arrested finger will be at one side of the printing point, indicated at p.

It will be observed that by my present invention I provide in combination a platen, types, case shifting devices, a ribbon vibrator, a support or supporting means for the ribbon vibrator, and means constantly tending to shift said support or supporting means; that the said means also provides a support for the line gage; that the case 95 shifting devices in the present instance effect a shift of the platen and platen carrier; that said support or supporting means supports directly certain of the key controlled, vibrator actuating devices, in the 100 present instance the operating lever, and through said operating lever supports the ribbon vibrator itself; that said support is a frame which is movably connected with the frame of the machine through a linkage 105 comprising two sets of double toggles, that is, each set includes two pairs of toggles; that the means constantly tending to shift the support for the operating lever and vibrator comprises spring means, this spring 110 means consisting of two coiled springs, each arranged diagonally of one of the sets of double toggles; that through the linkage the supporting frame is given parallel motion, that is, points on it move in substantially 115 straight paths or lines that are parallel with each other; that the spring means is restrained normally by stop devices which prevent the spring means from shifting the support; that these stop devices comprise a stop on the platen carrier or carriage and one on the shiftable support; that the stop on the platen carrier is a bar secured at its ends to the platen carrier and having a horizontal surface, while the stop on the support is a roller which contacts variably with the bar as the platen carrier and bar travel to and fro; that the spring means operates 120 125

to shift said support automatically when said case shifting devices are operated; that as a result of the simultaneous or automatic shifting of the support when the case shifting operation occurs the normal relation of the platen and the ribbon vibrator and operating lever is the same in both case positions, that is, it is unvarying; and that while the point of engagement of the traveling stop 10 bar with the stop roller varies in one direction, that is, in the direction in which the stop bar and the platen carrier travel, the position of the stop bar and stop roller vary also in a direction at right angles to 15 this first named direction, that is, in an up and down direction, because of the case shifting operation.

Various changes may be made without departing from the spirit and scope of my 20 invention.

What I claim as new and desire to secure by Letters Patent, is:—

1. In a typewriting machine, the combination of a platen, types, case shifting devices, 25 a ribbon vibrator, a support for said vibrator, devices for actuating said vibrator at printing operation independently of said support, and means separate from said vibrator and from said devices constantly 30 tending to shift said support.

2. In a typewriting machine, the combination of a platen, types, case shifting devices, a ribbon vibrator, a vibrator support mounted independently of said case shifting devices, and means operating to shift said support when said case shifting devices are operated. 35

3. In a typewriting machine, the combination of a platen element, a type carrying 40 element, one of said elements being shiftable to change case, case shifting devices, a ribbon vibrator, a vibrator support, and means constantly tending to shift said support, said means being normally restrained by 45 said shiftable element.

4. In a typewriting machine, the combination of a platen element, a type carrying element, one of said elements being shiftable to change case, a ribbon vibrator, a vibrator 50 support movably mounted on the frame of the machine, and a varying connection between said vibrator support and said shiftable element.

5. In a typewriting machine, the combination of a platen element, a type carrying element, one of said elements being shiftable to change case, a ribbon vibrator, a vibrator support movably mounted on the frame of the machine, case shifting devices, and 60 spring means constantly tending to shift said support, said spring means becoming effective when said shiftable element is shifted.

6. In a typewriting machine, the combina-

tion of a platen, types, case shifting devices, 65 a ribbon vibrator, a support for said vibrator, a linkage connecting said support with the frame of the machine, and means constantly tending to shift said support.

7. In a typewriting machine, the combination of a platen, types, case shifting devices, a ribbon vibrator, a vibrator support mounted on the frame of the machine and having a parallel motion, and spring means constantly pressing said support and effective 75 to shift it when the case shifting operation takes place.

8. In a typewriting machine, the combination of a platen, types, case shifting devices, a ribbon vibrator, a support for said vibrator, means constantly tending to shift said support, and stop devices for limiting the shifting movement of said support. 80

9. In a typewriting machine, the combination of a platen, types, case shifting devices, a ribbon vibrator, a support for said vibrator, means constantly tending to shift said support, and shiftable stop devices for limiting the movement of said support. 85

10. In a typewriting machine, the combination of a platen, types, case shifting devices, a ribbon vibrator, a support for said vibrator, means constantly tending to shift said support, and stop devices for limiting the shifting movement of said support, said 90 stop devices shifting when said case shifting devices are operated. 95

11. In a typewriting machine, the combination of case shifting devices including a shiftable element, a ribbon vibrator, a support for said vibrator, means constantly tending to shift said support, and stop devices for said support, one of said stop devices being on said shiftable element. 100

12. In a typewriting machine, the combination of case shifting devices including a shiftable element, a ribbon vibrator, a support for said vibrator, means constantly tending to shift said support, and stop devices for said support, one of said stop devices comprising a horizontally arranged bar 105 secured at its ends only to said shiftable element. 110

13. In a typewriting machine, the combination of case shifting devices including a shiftable element, a ribbon vibrator, a support for said vibrator, means constantly tending to shift said support, and stop devices for said support, one of said stop devices comprising a bar mounted on said 115 shiftable element and the other of said stop devices including a roller mounted on said support. 120

14. In a typewriting machine, the combination of case shifting devices, a ribbon vibrator, a support for said vibrator, means constantly tending to shift said support, and stop devices for said support, one of said 125

stop devices comprising a traveling bar and the other stop device comprising a roller co-operative with said bar and maintained in constant engagement therewith by said means.

15. In a typewriting machine, the combination of case shifting devices, a ribbon vibrator, a support for said vibrator, means constantly tending to shift said support, and

10 stop devices for said support, one of said stop devices comprising a traveling bar and the other stop device comprising a roller co-operative with said bar and maintained in constant engagement therewith by said

15 means, said bar shifting with said shiftable element.

16. In a typewriting machine, the combination of a platen, a platen carrier, means for shifting said carrier, a ribbon vibrator,

20 a support for said vibrator movably mounted on the frame of the machine, and yielding means for maintaining a constant relationship between said platen carrier and said support.

25 17. In a typewriting machine, the combination of a platen, a platen carrier, means for shifting said carrier, a ribbon vibrator, a support for said vibrator movably mounted on the frame of the machine, a stop device on said carrier, a stop device on said support, and spring means for maintaining said stop devices constantly in engagement.

18. In a typewriting machine, the combination of a platen, a platen carrier, means for shifting said carrier, a ribbon vibrator, a support for said vibrator movably mounted on the frame of the machine, a stop bar on said platen carrier, a stop device on said support having a varying contact with said bar, and spring devices for maintaining said stop device constantly engaged with said stop bar.

19. In a typewriting machine, the combination of a platen, types, case shifting devices, a ribbon vibrator, key controlled actuating devices for said vibrator, a support which provides a mounting for certain only of said actuating devices, and means constantly tending to shift said support.

20. In a typewriting machine, the combination of a platen element, a type carrying element, one of said elements being shiftable to change case, a ribbon vibrator, key controlled actuating devices for said vibrator, means providing a support for certain only of said actuating devices, and means constantly tending to shift said supporting means but normally restrained by said shiftable element.

21. In a typewriting machine, the combination of a platen, a platen carrier, means for shifting said carrier, a ribbon vibrator, key controlled actuating devices for said vibrator, means providing a support for certain only of said actuating devices, said support

ing means being mounted on the frame of the machine, a stop device on said carrier, a stop device on said supporting means, and spring means for maintaining said stop devices constantly in engagement.

22. In a typewriting machine, the combination of a platen, types, case shifting devices, a ribbon vibrator, an operating lever for said vibrator, a support on which said operating lever is fulcrumed, and means con-

70

stantly tending to shift said support.

23. In a typewriting machine, the combination of a platen, types, case shifting devices, a ribbon vibrator, an operating lever for said vibrator, a support on which said operating lever is fulcrumed, said support

80

being mounted independently of said case shifting devices, and means operating to shift said support when said case shifting devices are operated to maintain an unvarying normal relationship between said platen and said ribbon vibrator and operating lever.

85

24. In a typewriting machine, the combination of a platen element, a type carrying element, one of said elements being shiftable to change case, a ribbon vibrator, an operating lever for said vibrator, a support on which said lever is fulcrumed, and means constantly tending to shift said support, said means being normally restrained by said shiftable element.

90

25. In a typewriting machine, the combination of a platen, a platen carrier, means for shifting said carrier, a ribbon vibrator, an operating lever, a support for said lever

100

movably mounted on the frame of the machine and shiftable with said carrier, and yielding means for maintaining the same normal relationship between said platen carrier and said support in both case positions of the platen carrier.

105

26. In a typewriting machine, the combination of a platen, a platen carrier, means for shifting said carrier, a ribbon vibrator, an operating lever, a supporting frame, parallel links connecting said supporting frame with a fixed support, a stop bar fixed at its ends to said platen carrier and having a horizontal stop surface, a roller on said supporting frame, and spring means for maintaining said roller engaged with the horizontal portion of said stop bar.

110

27. In a typewriting machine, the combination of a platen, a platen carrier, means for shifting said carrier, a ribbon vibrator, means for shifting the same, and means for restraining the action of said vibrator shifting means, said restraining means comprising a stop bar fixed at its ends only to said platen carrier.

120

28. In a typewriting machine, the combination of types, a traveling platen carrier, case shifting devices, a ribbon vibrator, key controlled actuating devices for said vibrator, shiftable supporting means for cer-

130

- tain only of said actuating devices, said means being mounted on the frame of the machine, a stop device on the platen carrier, a stop device on the supporting means, the 5 point of engagement of one of said stop devices with the other varying in one direction with the traveling movement of the platen carrier, the positions of said stop devices varying in a direction at right angles to the first 10 named direction with the case shifting operation, and means for maintaining said stops in constant engagement.
29. In a typewriting machine, the combination of a platen, types, case shifting devices, a ribbon vibrator, actuating devices therefor, a support on which certain of said actuating devices are mounted, a linkage connection between said support and the 15 frame of the machine, said connection comprising two sets of double toggles, and springs, one arranged diagonally of each set of double toggles and tending constantly to shift said support.
30. In a typewriting machine, the combination of a ribbon vibrator, key controlled actuating devices therefor, means providing a support for certain of said actuating devices, means constantly tending to shift said supporting means, a stop for preventing the 20 operation of said shifting means, and means for moving said stop.
31. In a typewriting machine, the combination of a platen, platen shifting mechanism, a ribbon vibrator mounted independently of said mechanism, and constantly acting means effective when said platen is shifted to cause said vibrator to follow automatically the shifting movements of the platen.
32. In a typewriting machine, the combination of a platen, types, case shifting devices, a supporting frame, means constantly tending to shift said supporting frame, a ribbon vibrator on said frame, a line gage 25 mounted on said frame, and a ribbon vibrator supported from said frame.
33. In a typewriting machine, the combination of a platen, types, platen shifting mechanism, a ribbon vibrator, a line gage, said vibrator and said line gage being 30 mounted independently of said mechanism, and means for causing both said vibrator and line gage to follow automatically the shifting movements of the platen.
34. In a typewriting machine, the combination of a platen, types, case shifting devices, a line gage, a support for said line gage, and means controlled by said case shifting devices and constantly tending to shift said support.
35. In a typewriting machine, the combination of a platen element, a type carrying element, one of said elements being shiftable to change case, case shifting devices, a line gage, a line gage support, and means constantly tending to shift said support, said means being normally restrained by said shiftable element.
36. In a typewriting machine, the combination of a platen element, a type carrying element, one of said elements being shiftable to change case, a line gage, a line gage support movably mounted on the frame of the machine, case shifting devices, and spring means constantly tending to 40 shift said line gage support, said spring means becoming effective when said shiftable element is shifted.
37. In a typewriting machine, the combination of a platen, types, case shifting devices, a line gage, a support therefor, means constantly tending to shift said support, and shiftable stop devices for limiting the movement of said support, said stop devices shifting when said case shifting devices are 45 operated.

Signed at Ilion, in the county of Herkimer and State of New York, this 17 day of August A. D. 1915.

GEORGE A. SEIB.
